UNITED STATES PATENT OFFICE

2,451,696

SCREW HOLDING SCREW DRIVER

Michael J. Sopczak, Midland, Mich.

Application December 1, 1944, Serial No. 566,091

2 Claims. (Cl. 145—50)

1

This invention relates to certain new and useful improvements in screw-drivers and has more particular reference to the type of screw-driver which has embodied therein manually controlled mechanical means characterized by an oscillatory locking-bit, this to coact with the regular main bit on the shank of the screw-driver so that the bits can be arranged in relation to each other to bind and anchor themselves in the kerf or slot of the screw, thus providing means under the complete control of the user to hold the screw for starting purposes.

In carrying out the principles of the invention, I have evolved and produced a screw-driver having a so-called kerf lock for holding the screw, the arrangement being simple and durable in construction, reliable in operation, well balanced, comparatively inexpensive to manufacture and otherwise possessed of such advantages and functions as to serve as an ordinary screw-driver.

A further object is to provide a screw starter and holder attachment for a screw-driver the complete assemblage being easy to use, practicable and expedient in operation and otherwise adequate in fulfilling the requirements of a structure of this type. A still further object is to provide a screw starter or holder which easily attaches to the slot or kerf of the screw head and which firmly grips the parallel edges, but when sufficient pressure has been applied to the screw, instantly releases itself and is free to be removed.

Briefly, the preferred embodiment of the invention comprises a tubular shank having usual screw kerf engaging bits at its working end, there being a handle at the opposite end and said handle being hollow and in the form of a cylinder constituting a housing or container for the mechanism of the starter and screw holding means.

More specifically, novelty is predicated upon the adoption and use of a hollow handle receiving the adjacent spring-equipped end portion of the oscillatory screw lock or starter, the arrangement at this point embodying an end thrust disk integrally mounted on the oscillatory member, an end thrust washer at the opposite end of the spring, the spring being connected to the washer and to the oscillatory member and being of a compressional and torsional type.

Other features and advantages will become more readily apparent from the following description and the accompanying illustrative drawings.

In the drawings, wherein like numerals are used to

2

employed to designate like parts throughout the same:

Figure 1 is an elevational view of a screw-driver embodying a starter mechanism and lock constructed in accordance with the principles of this invention, the parts being shown mainly in dotted lines.

Figure 2 is a longitudinal sectional view with parts in elevation to bring out the construction and arrangement in particularity.

Figure 3 is a cross section on the plane of the line 3—3 of Figure 1 looking in the direction of the arrows and showing the screw lock means in what may be referred to as "gripping" position.

Figure 4 is a view like Figure 3 showing the screw locking mechanism in "released" position.

Figure 5 is an elevational view of the main unit or part of the oscillatory spring-projected screw lock.

Figure 6 is an elevational view of the hollow handle.

Figure 7 is a section on the line 7—7 of Figure 1 looking in the direction of the arrows, this showing the bits on the screw-driver proper and locking bit intervening therebetween and showing all of said parts in alignment constituting what may be called "neutral" position.

Figure 8 is a view like Figure 7 with the locking bit slightly canted for driving the screw.

Figure 9 is a view like Figure 8 showing the three bits shifted in relation to each other and the kerf for unthreading.

Figure 10 is a cross-section on the line 10—10 of Figure 1.

Figure 11 is a sectional view of the washer.

Figure 12 is a bottom plan view of the shank, this greatly enlarged to bring out the two bits on the screw-driver shank and the intervening oscillatory locking bit on the screw starter.

As before indicated, the handle 11 is in the form of a hollow cylinder. It has a reduced neck 12 at its bottom surrounding and secured to the adjacent inner end of the shank 13, the latter having a central bore passing therethrough. The outer end of the shank is concaved as at 14 (see Figure 12) whereby to adapt it to convex head screws as well as flat head screws. In this concavity I provide diametrically opposite stationary bits 15 which engage in the kerf or slot 16 of the screw 17 (see Figures 7, 8 and 9). Referring again to the handle and to Figures 1 and 2, it will be seen that the neck 12 joins the body portion by way of a conical web 18 thus forming a sort of a conical seat. The upper end of the handle is internally screw-threaded to accom-

modate the screw-threaded plug portion 19 of a closing plug 20, the latter being provided on its interior with an end thrust button 21 axially arranged.

The main part of the screw lock or screw starter is shown in Figure 5. This can be unitarily referred to as an oscillatory plunger 22. It has a reduced stem or rod portion 23 which extends down through the bore in the shank and terminates in a bit 24 which works back and forth between the spaced bits 15 as shown in Figures 7, 8, 9 and 12. The upper end of the rod as indicated at 25 is slightly enlarged to accommodate the coiled spring 26, the spring having its lower end anchored in a hole 27 formed in said part 25, the latter is provided at its top with a notch 28 to accommodate a small screw-driver for tensioning the spring 26. The spring is a compressional as well as torsional element and its upper convolutional end is bent laterally and anchored in a notch 29 in a ring or washer 30, the latter arranged in the upper end of the handle and held in place by a set-screw 31 (see Figure 2). Thus, the coil spring surrounds the part 25 and rests at one end against the washer 30. The opposite end rests against the disk like portion 32 or shoulder formed on the plunger. The underside of the disk-like portion is of a tapered or conical form as indicated at 33 to cooperate with the accommodation seat 18. A finger-grip comprising a button 34 has its shank threaded into the periphery of the shoulder 32, said shank working back and forth in an arcuate slot 35 provided in the handle.

The spring 26 exerts a torsional twist and the tension of this can be regulated. In doing this the plug 20 is removed and the screw-driver is placed in the slot 28. The finger-grip 34 is removed from the slot 35. Then the spring is wound up, so to speak, with the screw-driver until the desired number of turns have been made. By registering the socket in the periphery of the part 32 with the slot 35 the operating finger-piece 34 is replaced to maintain the parts properly assembled and tensioned.

In practice, the three bits 15, 24 and 15 are arranged in alignment with each other as shown in the so-called neutral position in position in Figure 7. This is done by moving the finger-grip 34 so as to line up the several bits whereupon they are shoved down and into the kerf of the screw 17. Then, by releasing the finger-grip 34 the spring means comes into play and cant or twists the central bit 24 which becomes a locking element. This "kicks" the other bits over into the slot of the screw as shown in Figure 8 for driving purposes. An alternative shift of parts is made by shifting the bits to the other position as seen in Figure 9 for unthreading. Consequently, the oscillatory lock, under spring torsional compression serves to definitely engage the end of the screw-driver with the kerf in the screw, holding the screw thereon for either inserting or removing during the "starting" step.

The complete operation can be made with the device as a screw-driver or a separate screw-driver can be employed for heavy duty work. It is primarily a "starter."

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrange-

ment of details coming within the field of invention claimed may be resorted to in actual practice, if desired.

I claim:

1. A screw-driver of the class described comprising an elongated hollow cylindrical handle open at its normally upper end, the opposite end of said handle being circumferentially tapered and defining a correspondingly tapered end portion for the bore merging into a centrally positioned and reduced hollow neck, a screw-driver shank fitted into and secured in said neck, said shank having a central bore extending entirely therethrough, the outer end of said shank terminating in opposed kerf-engaging main bits, a plunger device, embodying an enlarged disc-like shoulder having a conical portion rotatably engaging the tapered end portion of the bore of said handle, having an integral stem extending downwardly from said shoulder and rotatably through the bore in said shank and terminating at its outer end in an auxiliary bit arranged between the first named main bits, said handle having an arcuately extending slot formed in the side, a finger-grip exteriorly disposed in respect to said handle and having a part extending interiorly into the handle by way of said slot and removably connected with a marginal portion of said shoulder, said stem having an enlarged integral upper end located and confined in said handle and projecting above said shoulder and having at its upper end a notch to accommodate a screw-driver, spring abutting and anchoring means fixedly mounted in the upper end portion of said handle, the enlarged portion of said stem being slidably and rotatably mounted in and extending above said means, and a coiled torsional spring confined in said handle and surrounding the enlarged portion of said stem, one end of said spring bearing upon said shoulder and being anchored on said stem and the other end portion of said spring bearing against said means and being anchored on the latter means.

2. A screw-driver of the class described comprising an elongated hollow cylindrical handle having a bore internally screw-threaded and open at its normally upper end, the opposite end of said handle being circumferentially tapered and defining a correspondingly tapered end portion for the bore and merging into a centrally positioned and reduced hollow neck, a screw-driver shank fitted into and secured in said hollow neck, said shank having a central bore extending entirely therethrough, the outer end of said shank terminating in opposed kerf-engaging main bits, a plunger device, embodying an enlarged disc-like shoulder having a conical portion rotatably engaging the tapered end portion of the bore of said handle, having an integral stem extending downwardly from said shoulder and rotatably through the bore in said shank and terminating at its outer end in an auxiliary bit arranged between the first named main bits, said handle having an arcuately extending slot formed in the side, a finger-grip exteriorly disposed in respect to said handle and having a part extending interiorly into the handle by way of said slot and removably connected with a marginal portion of said shoulder, said stem having an enlarged integral upper end located and confined in said handle and projecting above said shoulder and having at its upper end a notch to accommodate a screw-driver, a coiled spring abutting and anchoring washer fixedly mounted in the upper end portion of said handle,

the adjacent notched end portion of said stem extending slidably and rotatably through and above the washer, a coiled torsional spring confined in said handle and surrounding the enlarged portion of said stem, one end of said spring bearing upon said shoulder and being attached to said stem and the other end of said spring bearing against said washer and being secured to said washer, and a screw plug threaded into the screw-threaded end portion of the handle above the notched end of said stem.
